No. 800,294.

PATENTED SEPT. 26, 1905.

W. W. HALLENBECK.
TROLLEY POLE AND STAND.
APPLICATION FILED JAN. 12, 1905.

FIG. 1.

UNITED STATES PATENT OFFICE.

WILLIAM W. HALLENBECK, OF BURRVILLE, CONNECTICUT.

TROLLEY-POLE AND STAND.

No. 800,294.

Specification of Letters Patent.

Patented Sept. 26, 1905.

Application filed January 12, 1905. Serial No. 240,848.

To all whom it may concern:

Be it known that I, WILLIAM W. HALLENBECK, a citizen of the United States, residing at Burrville, in the county of Litchfield and State of Connecticut, have invented certain new and useful Improvements in Trolley-Poles and Stands, of which the following is a specification.

This invention relates to overhead-trolley construction embodying a special construction of base or stand for the trolley-poles of cars.

The invention aims, primarily, to secure a device of the above class which admits of free movement of the pole with relation to its support in order that it may readily accommodate itself to curves in the feed-wire.

The invention provides a support which affords a bearing for the pole, having a minimum amount of friction; and at the same time a special structural feature of the invention consists in the provision of parts whereby the base may be used in connection with various types of swiveled heads by which the poles are ordinarily mounted upon the base.

For a full description of the invention and the merits thereof and also to acquire a knowledge of the details of construction of the means for effecting the result reference is to be had to the following description and accompanying drawings.

While the invention may be adapted to different forms and conditions by changes in the structure and minor details without departing from the spirit or essential features thereof, still some of the preferred embodiments are shown in the accompanying drawings.

Figure 1 is a plan view of a base constructed in accordance with the invention, the body of the head being removed. Fig. 2 is a vertical sectional view. Fig. 3 is a sectional view showing a modified form of pivot or stud.

Corresponding and like parts are referred to in the following description and indicated in all the views of the drawings by the same reference characters.

As is customary in devices of the nature above set forth, a suitable base 1 is provided which is adapted to be attached to the roof of a car by suitable fastenings. The base 1 is of peculiar form having a tubular extension 2, closed at the lower end and projected from the under side of said base. The pivot or stud 3 ordinarily employed to support the head carrying the trolley-pole is mounted in the extension 2, and for this purpose a sleeve or

similar tubular part 4 is disposed in the extension 2, being held in place by screws 5, threaded into adjacent portions of said sleeve and the base 1. The sleeve 4 is provided with raceways 6 at its upper and lower ends, and balls 7 are mounted in said raceways, affording a ball-bearing for the pivot 3 in a manner clearly apparent. The balls 7 at the lower portion of the pivot 3 are supported by a bearing-plate 8, having a raceway in the upper side thereof in which said balls are mounted. The plate 8 is provided with an opening through which the lower extremity of the pivot 3 passes, and said pivot is centralized by the plate 8 as regards its position in the sleeve 4. The extension 2 is designed for use as an oil-cup, and the pivot 3 is thoroughly lubricated by means of the member 2 when the latter is filled with a suitable lubricant. The pivot 3 is shouldered near the upper extremity of the sleeve 4, the upper ball-bearing 7 being below the shoulder 9, which latter is annularly formed upon the pivot. The pivot 3 is prevented from displacement by a cotter-pin or like member 10, which pin 10 passes through a transverse opening at the lower extremity of the pivot 3, co-operating with the bearing-plate 8 to prevent displacement of the pivot aforesaid. A head 15 carries the trolley-pole and is mounted upon the pivot 3, said head comprising a body 11 and attaching-plate 12 upon the under side of the body 11. The plate 12 is secured to the body of the head by means of screws 13 or like fastenings and is thereby rigidly attached to the member 11 in a manner apparent. The body 11 of the head is connected with the pivot 3 by means of a transverse pin or pins 14, which pass through the upper end portion of the pivot and adjacent portions of the head.

The head 15 is of a form similar to those in common use, having lateral arms 16, which carry the coil-springs by which the pole (not shown) is held in contact with the feed-wire above the car. The pole is mounted upon the head 15 in the usual manner, and an essential feature of the invention is comprised in the peculiar mounting of the head with reference to the base 1, whereby said head is adapted for free movement, so that the pole carried upon the same will readily accommodate itself to the curves of the trolley-wire and relieve the springs upon the arms 16 of much tension. These springs may therefore be adjusted so as to have a less amount of ten-

sion than those now in common use, because of the peculiar mounting of the head 15, which permits free movement of the pole, so that the pole-wheel is not likely to be displaced from the feed-wire and wear upon the said wheel and wires is greatly reduced, conducive to a longer life of these parts. The above affords quite a saving of expense, considering the trolley system as a whole.

10 The head 15, though swivelly mounted upon the base 1 through the pivot-pin 3, is not entirely supported by this pivot, having an independent bearing upon the base, which distributes the wear and permits a greater freedom of movement of the head with relation to the said base. To secure an independent bearing of the head, as above mentioned, the base 1 is provided with an annular seat 17, concentric of the sleeve 4 or extension 2 and surrounding the latter parts. The seat 17 receives upper and lower bearing-rings 18 and 19, respectively, between which are mounted roller-bearings 20. The uppermost ring 18 aforesaid is annularly recessed near its upper portion, so as to receive an integral flange 21, extending downwardly from the plate 12 and receiving the upper portion of the ring 18. An annular flange 22 projects upwardly from the base 1, and the inner wall of this flange 25 is approximately flush with the outer wall of the seat 17. The flange 22 is reduced at its upper portion, as shown at 23, the reduced portion being received in an annular kerf or groove 24 upon the under side of the plate 12.

30 The parts 18 and 21 have an interlocking connection virtually, and the overlapping parts 22 and 23 are such as to afford an effective means for excluding dust or other foreign matter from the bearings upon which the head 35 and pivot 3 are mounted. The plate 12, which is mounted upon the body 11 of the head 15, is of course adapted for rotary movement with said head, and this plate has a bearing upon the ring 18, between which and the ring 19 40 is interposed the roller-bearing 20. It will thus be seen that the head is supported freely for swivel movement upon the pivot 3, the bearings of which have a minimum amount of friction, and at the same time the head 15 45 is supported upon the roller-bearings 20 through a medium of the parts 12 and 18. The strain upon the head 15 is thus distributed over the base, the pivot 3 is relieved of a great deal of the strain, and the swivel 50 mounting of the head is equalized, so as to admit of movement of the same with a minimum amount of friction, advantageous in accommodating for the curves of the trolley-wire and, further, of important advantage in reducing the wear of the parts and increasing the general durability of the device. Before arranging the several parts of the base and head in operative positions the cup or extension 2 55 is filled with a lubricant, and such lubricant 60 will supply the bearings for a long time with-

out renewal. Further, if after long use it is found that the parts of the device have become loose because of wear the same may be readily reground at a nominal cost and will sustain continued use.

The numeral 25 in the drawings indicates the set-screws holding the wires by which the current is transferred from the pole to the fields or magnets controlling the mechanism of the car.

75 Fig. 3 of the drawings illustrates a modification in the construction of the pivot with regard more particularly to the manner of attaching the same to the base. Instead of utilizing the cotter-pin 10 the lower extremity 80 of the pivot 3 is threaded to admit of mounting of a nut 26, which holds the lower ball-bearings 6 in position forming a bearing member therefor. A jam-nut or like member 27 may be threaded upon the lower extremity 85 of the pivot to coöperate with the nut 26 and prevent displacement of the latter.

90 The provision of the attaching-plate 12 is of important advantage in that heads of different types may be secured thereto, thereby admitting of a broad application of the base or stand for use in connection with different constructions of heads, such as are now being used in different trolley systems.

95 Having thus described the invention, what is claimed as new is—

1. In a base or stand for trolley-poles, the combination of a base, a pivot mounted upon said base, a head mounted upon the pivot, the base being provided with a seat concentric of the pivot, a bearing-ring in the seat aforesaid, and antifriction-bearings interposed between the bearing-ring and the head.

2. In a base or stand for trolley-poles, the combination of a base, a pivot mounted upon 105 said base, a head mounted upon the pivot, the base being provided with a seat concentric of the pivot, a bearing-ring in the seat aforesaid, a second bearing-ring above the first-mentioned bearing-ring, antifriction-bearings interposed between the said rings, and an interlocking connection between the upper ring and the head.

3. In a base or stand for trolley-poles, the combination of a base, a pivot mounted upon 115 said base, a head mounted upon said pivot, said head comprising a body and an attaching-plate, and antifriction-bearings between the attaching-plate and the base.

4. In a base or stand for trolley-poles, the combination of a base having a tubular extension projecting from its under side, a pivot mounted in said tubular extension, means for preventing displacement of the pivot from the tubular extension, antifriction-bearings between the pivot and the base, a head mounted upon the pivot, and antifriction-bearings between the head and the base.

5. In a base or stand for trolley-poles, the combination of a base having a tubular ex- 130

tension, a sleeve affixed to the base within the tubular extension aforesaid, a pivot mounted in the said sleeve, antifriction-bearings between the sleeve and the pivot, a head mounted upon the pivot and comprising a body and an attaching-plate secured thereto, the base being provided with a seat concentric of the pivot aforesaid, bearing-rings disposed in said seat, and antifriction-bearings between said rings,

the attaching-plates of the head coöperating to with the rings aforesaid as specified.

In testimony whereof I affix my signature in presence of two witnesses.

WILLIAM W. HALLENBECK. [L. S.]
